UNITED STATES PATENT OFFICE.

WILLIAM B. STERRIT, OF PITTSBURG, PENNSYLVANIA.

MACHINE FOR FORMING GREEN-SAND CORES FOR JOURNAL-BOXES.

SPECIFICATION forming part of Letters Patent No. 470,518, dated March 8, 1892.

Application filed July 14, 1891. Serial No. 399,495. (No model.)

To all whom it may concern:

Be it known that I, WILLIAM B. STERRIT, a citizen of the United States, residing at Pittsburgh, in the county of Allegheny and State 5 of Pennsylvania, have invented certain new and useful Improvements in Machines for Forming Green-Sand Cores for Journal-Boxes; and I do hereby declare the following to be a full, clear, and exact description of the invention, reference being had to the accompanying drawings, which form part of this specification.

This invention has relation to machines for making green-sand cores for hollow castings, 15 and has for its object the provision of novel means for compressing green sand into the desired shape and around a suitable core-arbor by the operation of machinery, so as to obviate the laborious and costly method of 20 preparing dry-sand cores now extensively practiced.

My invention relates particularly to machines for making green-sand cores for casting railway journal-boxes, and has as its 25 special object the provision of means for forming a green-sand core for railway journal-boxes with the portion of the core which forms the top and bottom of the journal-box in a vertical direction. In some foundries 30 it is customary to cast journal-boxes in the position in which they set when in use, while in others they are cast lying on the side, and in forming green-sand cores it is desirable to form them in such manner that it will not be 35 necessary to turn them over when placing them in the mold, as a very slight jar is sometimes sufficient to destroy the core.

In an application for Letters Patent filed by me December 10, 1890, Serial No. 374,185, 40 I have shown and described a machine for forming green-sand cores in the position which the journal-box occupies when in use.

My present invention is designed to provide a machine which will form the green-sand cores upon the side; and it consists in the novel construction, combinations, and arrangements of parts, hereinafter described 45 and claimed.

Referring to the accompanying drawings, 50 Figure 1 is a plan view with the removable top of the machine swung to one side. Fig.

2 is a side elevation with the removable top in position on the machine. Fig. 3 is an end view of the machine. Fig. 4 is a sectional view on the line *xx* of Fig. 1, and Fig. 5 is a sectional view on the line *yy* of Fig. 1. 55

A A designate the side portions, and B the central portion of the frame, upon which the working parts of the machine are supported. The portion B is securely bolted to the sides 60 A A and is smooth and flat upon top and may be properly termed a "table." This table B has an orifice cut in it of the exact size and shape of the inside of the side of a journal-box, and in this orifice is fitted a solid plate 65 or block of metal C, which is moved up and down by mechanism to be presently described, and which constitutes a movable bottom for the core-box. Upon the bottom of the block C are formed sockets *c c*, in which rest the 70 ends of levers *d d*, pins *c' c'* serving to hold the levers in place in the sockets. The lower ends of the levers *d d* rest in sockets *e e* on the upper sides of strong curved levers E E, and are held in the sockets by pins *d' d'*. The 75 levers E E interlock in the manner of the leaves of a hinge and are fulcrumed upon a bolt *f*, which passes through hangers F F, depending from the table B. Near the lower ends of the levers E E and upon the inside of 80 the same are formed sockets *g g*, in which rest the outer ends of two toggle-levers G G, the levers being held in the sockets by pins *g' g'*. The inner ends of the toggle-levers G G rest in sockets *h h* in a vertically-movable 85 cross-head H and are held in the sockets by pins *h' h'*. The cross-head H slides in ways *i i* upon the inside of cross-bars I I, which are attached to the side frames A A of the machine, and a short link *k* is pivotally secured 90 to the bottom of the cross-head H, and its lower end is pivotally attached to a strong lever K, which is fulcrumed at *k'* to a standard *k''*, and projects through and is steadied in its movement by a vertical slot *I'* in the cross-bars I I. By moving the free end of the lever K up or down the movable bottom C of 95 the core-box is vertically reciprocated, moving up when the lever is pressed down and down when the lever is raised up. 100

Upon the table B rest and slide two heavy metallic sections L and L', the inside vertical

surface of the section L being shaped to correspond with the portion of a core which forms the top of a journal-box, while the opposing surface of the section L' is shaped to correspond to the formation of the bottom of the same. The sections L and L' form the sides of the core-box and when brought into position for forming a core their inside surfaces coincide exactly with the orifice in the table 5. By referring to the sectional view, Fig. 5, it will be seen that the sections L L' are hollowed out longitudinally and from their outer sides, and in the hollows are shafts L² L², which are journaled in bearings l l on the 10 edges of the side frames A A and have each on its outer end a small gear-wheel m m, both of which mesh with a large gear-wheel M, which is journaled on a stud M', that projects from the side frame A of the machine. Flat 15 plates N N are placed across the open sides of the sections L L' and are secured by bolts n n, and upon the shafts L² L² inside these plates are fixed cams L³ L³ that bear upon the plates N N and upon the vertical walls of the 20 sections L L', and serve when the shafts L² L² are turned to cause the sections to be simultaneously moved inwardly or outwardly, accordingly as the shafts move in one direction or the other. A lever M² projects from 25 the large gear-wheel M, and by means of this lever the said wheel M is moved whenever it is desired to cause the sections L L' to advance toward or recede from one another.

O designates the top of the core-box, which 30 is attached to the end of a screw O', passing through a swinging arch O², which is pivoted at one end to one of the side frames of the machine by an upright bolt o and at the other end abuts against a standard o' on the other side 35 frame, a toe o² on the arch entering a cavity o³ in the side of the standard and serving to prevent that end being lifted when the top O of the core-box is forced down by the screw O'. Pins o⁴ o⁴ project downwardly from the 40 arch and pass through holes in the top O, and serve to guide and steady the top in its movements.

P designates the core-arbor, which is a flat bar of metal sustained in the core-box by being supported at one by the straight vertical plate P' and at the other end by the bent vertical plate P². The ends of the core-bar pass through the holes in the plates P' P², and wedge-shaped keys p' p³ are driven through 45 holes in the bar to maintain the parts in their proper relative positions.

As the core-arbor and its appurtenant parts form no part of my present invention, being already secured to me by Letters Patent, it 50 need not be more particularly described.

The dust-chamber of the journal-box is formed by placing in the core-box and confining with the green sand a dry-sand dust-chamber core R. A concave block S is formed 55 on the bottom C and rises on one side of the core R when the said bottom is elevated, and

a slide T, which is cut out on its upper edge to conform to the concavity of the block S, passes through a slot in the bottom and rises on the other side of the core R. A block U 70 fits down over the top of the core R and has two edges r r that coincide with the concave block S and the slide T. The sides r r, the concave block S, and the slide T are cut away so as to leave an oblong opening, which corresponds to the opening in the end of the journal-box when cast. The slide T passes through a slot in the movable bottom C, as before stated, and is connected by a link t to a lever V, by means of which the slide may be raised 80 and lowered, as desired. A latch on the lever V serves to keep the lever and the slides in their elevated positions, engaging for this purpose with a notch in the end frame A.

The apparatus constructed as described is 85 operated in the following manner: The parts being in the positions shown in Fig. 1—that is to say, the bottom C lowered, the slide T raised, the sections L L' brought toward one another to their fullest extent of motion, the top raised, the arch swung back, and the core-arbor and the dry-sand core in their proper positions—the green sand is now poured into the space between the sections L L' and the end plates of the core-arbor until the space 90 is completely filled. The arch O² is then swung around into position and the screw O' turned, forcing the top down onto the sand in the core-box. A portion of the bottom of the top is in slight relief and corresponds to the 95 shape of the core-box and is forced down into the same by the action of the screw. The lever K is now pressed down, and this motion of the lever raises the bottom C, thus compressing the sand tightly in the core-box and 100 around the core-arbor and completely forming the green-sand core. The block U is now lifted out through a hole U', which is left for that purpose in the top of the core-box, and the slide T is lowered by releasing the 105 latch v on the lever V. The top O is now raised by turning the screw O', and the arch O² is swung around, carrying the top O away from over the core-box. The lever K is then raised, thus lowering the bottom C. The sections L L' are now moved outwardly by turning the gear-wheel M, and the completed core 110 now hangs suspended on the arbor which is supported at its ends by the vertical plates P' P², resting on the table B, outside the orifice 115 through which the bottom C works.

Having fully described my invention, I claim—

1. In a machine for forming green-sand cores for journal-boxes, the combination of a stationary table having an orifice corresponding to the shape of the sand core for a journal-box, a vertically-movable block fitted to said orifice and constituting the bottom of a core-box, a movable top adapted to cover and close the core-box with movable sections constituting the sides of the core-box, and mech-

anism, substantially as described, for moving the sides inwardly and outwardly and for vertically moving the bottom, as set forth.

2. In a machine for forming green-sand cores, the combination of the stationary table B, having an orifice corresponding to the shape of the core which is to be formed, the vertically-movable bottom C, fitting said orifice, means for reciprocating said bottom, the movable top O, and the movable sides L L', all constructed and arranged substantially as described.

3. In a machine for forming green-sand cores, the combination of stationary table B, having an orifice of the shape of the core to

be formed, the vertically-reciprocating bottom C, connected to and operated by the lever K, and intervening connections with the movable sides L L', the shafts L²L², carrying cams L³L³, which contact with and move the said sides L L', and means, substantially as described, for simultaneously revolving said shafts, as set forth.

In testimony that I claim the foregoing I have hereunto set my hand this 26th day of June, 1891.

WILLIAM B. STERRIT.
